UNITED STATES PATENT OFFICE.

BERN JASSEN, OF NEW YORK, N. Y.

DESIGN FOR A WINDSHIELD FOR AUTOMOBILES.

Application filed August 8, 1922. Serial No. 3,321. Term of patent 14 years.

To all whom it may concern:

Be it known that BERN JASSEN, a citizen of the United States, and resident of the city of New York, in the county of Kings and State of New York, has invented a new, original, and ornamental Design for Windshields for Automobiles, of which the following is a specification, reference being had to the accompanying drawing, forming part thereof, in which the figure is a vertical

elevation of a wind shield embodying my new design secured to a supporting bracket shown in dotted lines.

I claim:

The ornamental design for a windshield for automobiles as shown and described.

Signed at New York city, in the county of New York and State of New York, this 2nd day of August 1922.

BERN JASSEN.
